UNITED STATES PATENT OFFICE.

LOUIS WEIDLICH, OF STRATFORD, CONNECTICUT.

CIGARETTE-DISPENSING DEVICE.

Application filed October 23, 1923. Serial No. 670,272.

To all whom it may concern:

Be it known that LOUIS WEIDLICH, a citizen of the United States, and resident of Stratford, in the county of Fairfield and 5 State of Connecticut, has invented certain new and useful Improvements in Cigarette-Dispensing Devices, of which the following is a specification.

This invention relates to an improved 10 cigarette dispensing device, and has for its object to provide a device of this character in which a number of cigarettes may be contained, and by means of which they may be delivered singly, when desired. A further 15 object is to provide such a device in which the cigarettes will be protected against dust, dirt and breakage, and which will maintain them in a proper condition for smoking.

Other objects are simplicity of construction and freedom from parts which will readily get out of order.

With the above and other objects in view, an embodiment of the invention is shown in the accompanying drawings, and this embodiment will be hereinafter more fully described with reference thereto, and the invention will be finally pointed out in the claim.

In the drawings:

30 Fig. 1 is a perspective view of a cigarette dispensing device, according to the present embodiment of the invention;

Fig. 2 is a vertical sectional view thereof;

35 Fig. 3 is a similar sectional view, but showing the cigarette delivery means in a different operative position; and

Fig. 4 is a longitudinal vertical sectional view.

Similar reference characters indicate corresponding parts throughout the several figures of the drawings.

Referring to the drawings, the device comprises a rectangular outer casing 10, provided at the lower part of its front face 45 with a horizontal delivery slot 11, the lower edge of which is contiguous to a grooved forwardly projecting cigarette receiving portion 12, adapted to receive a single cigarette and permit of its convenient removal 50 with the fingers.

Within the outer casing there is supported a cigarette containing hopper, the front and rear walls 13 and 14 of which are spaced from each other at their lower ends to form 55 a base opening, the walls being curved in-

wardly toward said opening, while the side walls 15 and 16 are inclined downwardly and inwardly.

Beneath the hopper portion there is rotatably mounted a cigarette selecting and delivering member 17, in the form of a cylinder or drum, having disc shaped ends 18 and 19, and provided with a longitudinal pocket 20 formed integrally with the cylinder by bending, the ends of this pocket being closed by portions of the disc ends. The pocket corresponds and registers in length with the base opening of the hopper. At the side opposed to the pocket the drum is open, so that the longitudinal edges of the opening form stops to limit the rotation of the cylinder, and thereby determine its operative positions, as will presently more fully appear.

The delivery member is adapted to continuously close the base opening of the hopper, and by rotation from one position to the other deliver the cigarettes singly through the slot 11 to the receiving groove 12. For this purpose it is provided with 60 an axial shaft 21 fixed thereto by soldering or the like, as at 22, the ends of said shaft being journaled in the sides of the casing, one end projecting outwardly and being bent at right angles to form a manipulating handle 23. Collars 24 and 25 are provided on the shaft between the disk ends 18 and 19 and the sides of the casing to fix the longitudinal position of the delivery member.

A stop member 26 is secured to one of the 65 side walls of the casing, being bent inwardly and upwardly in a manner to engage within the opening of the drum and thereby abut the longitudinal edges, in one or the other positions, as shown in Figs. 2 and 3, 90 and thereby limit and determine the positions of the delivering member. The surface of the drum is preferably roughened, as at 27, so that it will tend to roll the cigarettes as the member is rotated, and thereby 95 insure their proper positioning.

A removable cover 28, which may be hinged or otherwise secured, is provided at the upper end of the casing to close the hopper and protect the cigarettes therein from 100 dust and dirt.

It will be noted that the walls of the hopper cause the cigarettes to assume longitudinal positions, and that the base opening is substantially wider than the pocket 20, so 110

that a number of cigarettes are always in position to be delivered, and the deposit of one of them in the pocket is insured.

The drum is so weighted, preferably by providing a surplus of metal at the rear of the pocket, as at 28, Fig. 2, that it will remain in the position with the pocket in the base opening of the hopper, until such time as a cigarette is desired, and will automatically return to such position, after being moved forward, as soon as the fingers are removed from the handle. When a cigarette is desired, the handle 23 is moved forwardly from the position shown in Fig. 2 to that of Fig. 3, the rotation of the drum being limited by abutment with the stop 24, so that the pocket is brought into register with the delivery slot, and the cigarette rolls from the pocket to the grooved receiving portion. The construction is very simple, and does away with the use of springs, levers, or other complicated mechanism, and at the same time is automatic in action.

I have illustrated and described a preferred and satisfactory embodiment of the invention, but it will be obvious that changes may be made therein, within the spirit and scope thereof, as defined in the appended claim.

Having thus described my invention, what I claim and desire to secure by Letters Patent is:

A device of the character described, comprising a casing having a front wall provided near its lower edge with a horizontal

grooved cigarette receiving portion, said front wall being provided with a horizontal slot having its edges in a vertical plane and having its lower edge coincident with the inner edge of said grooved portion, a cigarette containing hopper in said casing provided in its base with a horizontal opening having its edges in a horizontal plane above the upper edge of said slot of the front wall, the walls of said hopper being inclined inwardly toward said opening, a rotatable cylindrical cigarette selecting and delivering member mounted in the casing beneath said opening of the hopper and at the side of said slot of the front wall, the cylindrical surface of said member adapted to move through said opening and said slot to close them, said member being provided with a longitudinal pocket adapted to be moved upon rotation of said member between registering relation with said opening and registering relation with said slot, the surface of said pocket adapted in the latter position to be aligned with the surface of said grooved portion of the front wall whereby the cigarette delivered by said pocket rolls directly therefrom into said grooved portion, means for manually rotating said member, and limiting means adapted to limit the rotation thereof between said opening and slot registering positions of said pocket.

Signed at Bridgeport, in the county of Fairfield and State of Connecticut, this 10th day of October, A. D., 1923.

LOUIS WEIDLICH.
